UNITED STATES PATENT OFFICE.

ALBERT BIE, OF WINTERTHUR, SWITZERLAND, ASSIGNOR TO BUSCH-SULZER BROS.-
DIESEL ENGINE COMPANY, OF ST. LOUIS, MISSOURI, A CORPORATION OF MISSOURI.

ENGINE-CYLINDER.

1,227,240.

Specification of Letters Patent.

Patented May 22, 1917.

Application filed February 2, 1915. Serial No. 5,621.

To all whom it may concern:

Be it known that I, ALBERT BIE, a citizen of the Kingdom of Norway, residing in Winterthur, Switzerland, have invented a 5 new and useful Improvement in Engine-Cylinders.

This invention is an improvement in internal combustion engine cylinders and is concerned more especially with the structure 10 of the head or inner ends thereof, the object being to provide a construction whereby the water-cooling of the head may be more effective, which renders the cooling space accessible for cleaning and permits of re- 15 placement of the part exposed to combustion, and which is in general well adapted to withstand the strains to which this portion of the cylinder is subjected.

In the accompanying drawings illustrating the invention:

Figure 1 is a longitudinal section through the head portion of an internal combustion engine; and

Fig. 2 is a plan view thereof.

25 The invention is designed more particularly for internal combustion engines of the Diesel type, and it may be understood that the drawing represents a cylinder of an engine of this character. The body of the 30 cylinder may be cast in one piece, or, as shown, composed of an inner section *a*, in which the piston operates, and a separate outer jacket part *a'* inclosing a water cooling space in the lateral wall of the cylinder.

35 A head member *d* is separate from both portions of the cylinder body and is united thereto by bolts *h*, which pass through the head into the part *a'*, the part *a* being held in place by a flange *u* which rests on a shoul- 40 der *o* on the jacket. The head member is a casting made with an appropriate space or spaces *i*, *k* in its interior for circulation of

cooling water, to reduce the temperature of the part forming the end wall of the combustion chamber *b*, and with valve sockets *g* extending through the cooling spaces for the reception of the housings of valves *r* and *s*, which may be, respectively, a fuel-atomizing valve and an air-starting valve, the air

45 for scavenging or combustion being admitted through another valve in the head or through lateral ports, not shown. In the preferred form of the invention the cooling spaces *i*, *k* are separated by an inner trans-

verse wall *m* parallel with the top or outer 55 end wall *n*, and united with the encircling side wall *p*, the transverse walls being further united by the interiorly located valve studs, acting as post members, the inner 60 projecting ends of which are in supporting relation to the end wall of the combustion space as will now be described. In this way an exceptionally strong trussed construction 65 is secured and a favorable utilization of the cooling water made possible, in addition to 70 the other advantages enumerated herein- after.

The inner side of the head, which is left 75 open in the casting, is covered by a separate plate *c*, smaller in diameter than the head, 80 constituting part of the inclosure of the cooling space *i* and dividing the same from the combustion chamber. This plate is pro- 85 vided with openings *e* and *f* for the valves and is held at its circumference by the pres- 90 sure of the bolts *h* between an annular flange or shoulder *t* on the head and the part *a* of the cylinder body, where a recess and en- 95 gaging rib *v* are provided for securing a compression-tight joint for the combustion 100 chamber. In addition to the support thus afforded, the plate is sustained inwardly of its circumference against the pressure in 105 the combustion chamber by the inner por- 110 tions of the valve sockets *g*, which project within the space *i* so that their ends lie sub- 115 stantially in a plane with the flange *t*. The 120 said flange is located somewhat above the lower end of the encircling side wall of the 125 head, thereby forming an internal rabbet 130 which with the upper end of the cylinder part 135 *a* constitutes an annular recess or groove 140 wherein the plate is held, the plate being 145 somewhat smaller in diameter than the recess 150 as indicated, so as to permit of radial ex- 155 pansion of the plate relative to the head and cyl- 160 165 170 175 180 185 190 195 198 200 205 210 215 220 225 230 235 240 245 250 255 260 265 270 275 280 285 290 295 298 300 305 310 315 320 325 330 335 340 345 this wall to be made of special material selected with a view to resisting the conditions of heat and pressure to which it is subjected. The sockets *g* for the valves of the cylinder head may also be made in one piece with the plate *c* and the ends of the sockets may have bearing against the cylinder head. It will be understood that the drawing does not purport to show features and details unessential to the invention, and that, for example, wherever joints should be made tight in practice the usual expedients may be resorted to in actual construction.

I claim:

15 1. In an internal combustion engine having a cylinder head containing a cooling space and formed with a side wall encircling the same, a separate removable part at the inner side of said head bearing against 20 the encircling wall of the head and thereby closing off said cooling space from the combustion space.

25 2. In an internal combustion engine cylinder, the combination with a head member hollow for the circulation of cooling water and open at its inner side, the said head member being formed with an encircling side wall having an internal rabbet, of a 30 separate plate seated at its outer portion in said rabbet and covering said inner side of the head member and separating the cooling space therein from the combustion space.

35 3. In an internal combustion engine cylinder, the combination with a cylinder body and a separate cylinder head secured to the cylinder body, the head and body being formed to inclose between them an internal annular recess, the latter being hollow for the circulation of cooling water, of a part 40 interposed between said body and head and closing off the interior of the head from the combustion space, the said part being of smaller diameter than the head and received at its circumferential portion in said recess.

45 4. In an internal combustion engine, a cylinder body and a cylinder head member containing a cooling space open at its inner side, in combination with a separate part closing the inner side of said head member 50 and held adjacent its circumference between the same and the cylinder body, the head member having projections in its cooling space affording shoulders against which said part bears inwardly of its circumference.

55 5. In an internal combustion engine cylinder, the combination with a head formed with a cooling space and valve sockets extending through said cooling space, of a plate closing said cooling space off from the 60 combustion space and having bearing against the inner projecting ends of said valve sockets.

65 6. In an internal combustion engine cylinder the combination with a head formed with a cooling space, said head having a side

wall encircling said space, of a plate co-operating with said side wall to close said cooling space from the combustion space, said plate having sockets for the valves and the ends of these valve sockets having bearing against the cylinder head. 70

7. In an internal combustion engine cylinder the combination of a cylinder body, a hollow water-cooled head, and an interposed removable part constituting the inner wall of the cooling space in the head, the said part having a rib on its inner side entering a groove in the end of the cylinder body for the production of a compression tight joint. 75

8. In an internal combustion engine, a cylinder head comprising a hollow casting containing a cooling space, said casting being open at the inner side, in combination with a separate inner portion applied against the open end of the casting and having an internal surface finished off smooth to be washed by the cooling water. 80

9. In an internal combustion engine, the combination of a cylinder body, a hollow water-cooled head, and a plate forming the end wall of the combustion chamber, the said plate being mounted in a recess between the head and body and being capable of radial expansion therein relative to said parts. 90

10. An internal combustion engine cylinder having a body, a separate outer water-cooled head, an interposed removable part closing the inner side of the water space of the head and constituting the end wall of the combustion space, and means whereby said part is held in place with freedom for radial expansion relative to the other parts. 100

11. In an internal combustion engine, the combination of an outer cylinder part, a hollow head bolted thereto, said head and outer body part having internal ledges, an inner cylinder part, and a removable plate closing the inner side of the head, said inner cylinder part and said plate being held by and between said internal ledges. 110

12. In an internal combustion engine, the combination with a wall forming the end of the combustion space, of a hollow water-cooled head having a transverse inner wall and valve sockets united with said wall and with an outer part of the head and bearing at their inner ends as supports against the end wall of the combustion space. 115

13. In an internal combustion engine, the combination with a cylinder, of a hollow water-cooled head member, and a separate plate confined at its outer edge between the head member and cylinder and closing off the end of the combustion space from the water-cooling space in the head, said head member being of unit construction comprising outer and inner transverse walls and a side wall and valve sockets uniting the transverse walls, the inner ends of the valve sockets projecting beyond the inner trans- 120

verse wall and affording support to the interior part of the plate.

14. In an internal combustion engine, the combination with a cylinder, of an outer hollow water-cooled head member, and an inner member forming the end wall of the combustion space, said outer member being formed with side and top walls and an inner transverse wall dividing the water-cooling space, and valve sockets uniting said top

and inner walls and bearing at their inner ends against said inner member.

In testimony whereof, I have signed this specification in the presence of two witnesses.

ALBERT BIE.
